UNITED STATES PATENT OFFICE.

WILLIAM ROUTLEDGE, OF LONDON, ENGLAND.

LOOM SHUTTLE-BOBBIN.

1,385,952.

Specification of Letters Patent. Patented July 26, 1921.

Application filed July 6, 1920. Serial No. 394,278.

To all whom it may concern:

Be it known that I, WILLIAM ROUTLEDGE, A. M. I. E. E., a subject of the King of Great Britain, residing at Laurel Bank, 5 Hoop Lane, Golder's Green, London, England, have invented new and useful Improvements in Loom Shuttle-Bobbins, (for which I have applied for patent in Great Britain, June 23, 1919, Patent No. 151,360, 10 and Dec. 18, 1919, Patent No. 160,278,) of which the following is a specification.

My invention relates to the bobbins of shuttles used in looms for weaving.

As is well known, such shuttle bobbins 15 are usually made of a tapering wooden cylinder, the outer periphery of which is generally formed with a series of annular or spiral grooves for the purpose of preventing the weft unintentionally leaving the said 20 cylinder due to the impacts which the shuttle receives in its motion in the loom. Such bobbins frequently become broken in use and their replacement is a constant source of expense which, particularly at the present 25 time, is a matter of some importance.

Attempts have been made to substitute for such wooden bobbins, bobbins made from a sheet of metal, preferably tin-plate, which is wound spirally so as to form a taper tube 30 of the dimensions required and provided with spiral grooves, projections or the equivalent thereof.

According to my invention the adjacent edges of the spirally wound strip are seamed 35 or locked to one another so as to form, without the use of solder, cement or the like, a rigid tube provided with a spiral projection.

To enable the invention to be fully understood, I will describe it by reference to the accompanying drawing, in which—

Figure 1 is a sectional side view of a bobbin having one form of seam or locked joint according to the invention.

Figs. 2, 3, 4, 5 and 6 are sectional views 45 illustrating other forms of seam or locked joint.

Referring to Fig. 1, *a* indicates the strip which is spirally wound so as to form the 50 tapering tube. The edges of the strip which is thus spirally wound are formed into a

seam *b* which constitutes the projecting spiral required.

Fig. 2 is a view similar to Fig. 1 but illustrating a slight variation in this type 55 of seam, and Fig. 3 is a view illustrating the construction in which the seam is formed by a spiral clip piece *c* which engages the flanged adjacent edges *d* of the spiral strip *a* in the manner clearly indicated.

Fig. 4 shows a construction in which the seamed or locked joint is formed by overlapping the adjacent edges of the spirally wound strip of metal and then forming a 65 groove *e* therein exterior to the bobbin 60 whereby the said edges are locked together and the necessary spiral groove is provided for the bobbin. The groove *e* is shown of semicircular form in cross section.

Fig. 5 shows a similar construction to Fig. 4 but showing the groove *e* formed in the interior of the bobbin whereby the spiral projection *f* is produced on the exterior thereof.

Fig. 6 shows a similar view to Fig. 5, 75 the groove *e* being, however, of V-form in cross section.

What I claim and desire to secure by Letters Patent is:—

1. A loom shuttle bobbin composed of a 80 strip of metal spirally wound to form a taper tube, the adjacent edges of the spirally wound strip being in interlocking engagement with one another in such a manner as to form a rigid tube provided with a spiral 85 projection, substantially as set forth.

2. A loom shuttle bobbin composed of a strip of metal spirally wound to form a taper tube, the adjacent edges of said strip being bent to form a spiral projection. 90

3. A loom shuttle bobbin composed of a strip of metal spirally wound to form a taper tube, the adjacent edges of said strip being hook-shaped in cross sections, said hook-shaped portions being adapted to interlock. 95

4. A loom shuttle bobbin composed of a strip of metal spirally wound to form a taper tube, the adjacent edges of said strip being bent to form projections, and means 100 for securing the projecting parts together.

WILLIAM ROUTLEDGE.
